UNITED STATES PATENT OFFICE.

JOHN KRAUS, OF PITTSBURGH, PENNSYLVANIA.

FINGER RING.

Application filed February 29, 1924. Serial No. 696,052.

To all whom it may concern:

Be it known that I, JOHN KRAUS, a citizen of the United States, and resident of Pittsburgh, in the county of Allegheny and State 5 of Pennsylvania, have invented a new and useful Improvement in Finger Rings; and I do hereby declare the following to be a full, clear, and exact description thereof.

My invention relates to finger rings and 10 particularly to an arrangement whereby two rings may be combined to form a unitary structure.

One of the objects of my invention is to 15 provide means whereby an engagement ring, for example, may be so formed that another ring, such as a wedding ring, may be attached thereto to form a single article of jewelry.

Ordinarily engagement rings and 20 wedding rings are worn on a single finger as separate articles, but as the mounting of the engagement ring is relatively large in cross section as compared to the band portion thereof, the wedding ring will not lie 25 snugly against the engagement ring, with the result that the rings occupy too much space on the finger and mar the ornamental effect desired. In addition to this objection, the contrast between the plain wedding ring 30 and the more ornamental engagement ring is too great.

By my invention it is possible to combine 35 a wedding ring and an engagement ring in such manner that they may be worn with comfort, and the beauty of the engagement ring is not detracted from by the presence of the wedding ring, while at the same time the wedding ring is easily discernible upon close inspection.

One form which my invention may take 40 is shown in the accompanying drawing wherein Fig. 1 is a view, in side elevation, of an engagement ring embodying my invention; Fig. 2 is a view thereof, in edge elevation; Fig. 3 is a view similar to Fig.

2, particularly in section; Fig. 4 is a side elevational view, in section; Fig. 5 is a view of the wedding ring, and Figs. 6 and 7 are, respectively, sectional views in side and edge elevation, of the rings in assembled relation. 50

While my invention is shown and described as applied to wedding and engagement rings particularly, I do not limit myself to the employment thereof in connection with only those specific types of rings. 55

The engagement ring consists of a mounting portion 2 and a band portion 3 that is composed of spaced portions 4 and 5 which, at the time the ring is formed, are connected by a tie or lug portion 6, the portions 4 and 5 being ordinarily formed by slitting the band member 3 but leaving the portion 6 to serve as a support for the divided sections 4 and 5 until the time when it is desired to insert the wedding ring 7. The 60 inner and outer surfaces of the ring 7 are preferably substantially flush with the corresponding surfaces of the members 4 and 5 when in assembled position. The tie portion 6, while sufficient to support the divided 65 portions 4 and 5, is of such small cross section that it may be readily cut away at the time of the wedding to permit insertion of the 70 wedding ring.

What I claim is:

1. A ring provided with a mounting portion, axially spaced annular portions integral with said ring, and a lug of small cross sectional area uniting said annular portions at a point substantially diametrically opposite to said mounting portion. 75

2. A ring comprising axially spaced annular portions permanently united at one point, and a lug for temporarily uniting said portions at a point substantially diametrically opposite to said first-named point. 85

In testimony whereof I, the said JOHN KRAUS, have hereunto set my hand.

JOHN KRAUS.
